ABSTRACT

A honing apparatus for super finishing the bore surface of a machine part and particularly the epitrochoidal bore surface of the stator part of a Wankel engine. The apparatus includes mounting structure for mounting three honing stones internally of the stator for movement in the same manner as the rotor of the Wankel engine. The apparatus further includes control mechanism for moving the honing stones into and out of contact with the bore surface of the stator.

FIG. 6

HONING APPARATUS

BACKGROUND OF THE INVENTION

In the construction of the stator part of a Wankel engine, the internal bore is formed to an epitrochoidal shape. The final formation of this shape is usually done by a grinding operation after which the stator is ready for use in the Wankel engine. If the grinding operation does not provide a completely uniform surface, the use of the stator without further surface finishing of the bore may produce improper engagement between it and the rotor part of the engine. Where the grinding operation does not provide an acceptable surface finish, subsequent polishing is necessary. Usually, this polishing, if done at all, is done by hand which, of course, is a time-consuming and expensive operation.

SUMMARY OF THE INVENTION

In accordance with the teachings of the present invention, applicant has developed a honing apparatus particularly suited for polishing the internal epitrochoidal bore surface of the stator of a Wankel engine. This honing apparatus can be most advantageously used where the prior grinding of the bore surface has not formed an acceptably uniform surface finish. Also, even where the prior grinding has produced an extremely accurate and uniform surface, subsequent polishing with the honing apparatus of the present invention may be desirable.

In construction, the honing apparatus generally includes a rotor housing rotatably positioned within the bore of the stator for movement in precisely the same manner as the rotor of the Wankel engine will move inside this stator. Fixed to the rotor housing are three honing stones. These stones are spaced from each other and located in contact with the internal bore surface of the stator in the same manner as the three sealing members which are included on the rotor of a Wankel engine. With the above construction, the honing stones will follow a path identical to that normally followed by the rotor of the Wankel engine. Thus, the complicated epitrochoidal shaped surface of the bore of the stator will be accurately followed by the honing stones to produce accurate polishing of this surface.

With applicant's honing apparatus, control means are provided for adjusting the position of the honing stones within the bore of the stator workpiece being honed. This control means is used to move the honing stones under some degree of pressure against the internal bore surface and to hold it in this position during the honing operation. The control means is also operable to move the honing stones away from the surface being honed to permit removal of the honing apparatus from the finished stator workpiece and to permit entry of the next workpiece to be honed.

BRIEF DESCRIPTION OF THE DRAWINGS

FIG. 1 is a side view partially in cross section of the preferred embodiment of the honing apparatus of the present invention;

FIG. 2 is a cross-sectional view taken along lines 2—2 of FIG. 1;

FIG. 3 is a cross-sectional view taken along lines 3—3 of FIG. 2;

FIG. 4 is a plan view of the apparatus shown in FIG. 1;

FIG. 5 is a side view of the foot treadle mechanism used for controlling the honing operation; and

FIG. 6 is a side view partially in cross-section of an alternative embodiment of the honing apparatus of the present invention.

DESCRIPTION OF THE PREFERRED EMBODIMENTS

As shown in FIGS. 1 and 2, the honing apparatus generally includes an upright support structure 1 for slidably holding the honing mechanism 2 for vertical movement in overlying alignment with a workpiece 3 such as the stator part of a Wankel engine. The workpiece is, in turn, mounted on support means generally designated at 4. The lower end of the honing mechanism includes a honing rotor housing 5, most clearly shown in FIG. 3, to which are secured three honing members 6 for engaging against the internal bore surface 7 of the stator workpiece. As shown, this surface 7 defines an epitrochoid.

In order to permit entry of the rotor housing and honing members into the bore of the stator workpiece, the honing mechanism 2 is slidably mounted on the support structure 1 by way of the dovetailed connection 8 shown in FIG. 4. Sliding movement of the honing mechanism is effected by actuation of a hydraulic power cylinder 9 mounted on the support structure 1 by a bracket 10. The piston rod 11 of the power cylinder is connected by a bracket 12 to a slide support structure 13 in which a dovetailed slot is cut for the connection 8. Extension and retraction of the piston rod of the hydraulic power cylinder will cause lowering and raising of the honing mechanism into and out of operative association with the stator workpiece to be honed.

For rotating the rotor housing within the bore of the stator workpiece, an internal gear 14 is fixed to the upper surface of the rotor housing in meshing engagement with a stationary gear 15 fixed to the slide support structure 13. The internal gear 14 has a 3:2 gear ratio with the fixed gear 15 which is located concentrically relative to the central axis 3' of the stator workpiece. A drive shaft 16 extends perpendicular to the plane in which the workpiece lies and coaxially through the stationary gear 15. At its lower end, the drive shaft is connected to the rotor housing to effect rotation thereof as more fully described below. A sleeve bearing 17 is secured in the bore of the stationary gear for rotatably supporting the drive shaft at its lower end. A second sleeve bearing 18 is secured to the slide support structure 13 for rotatably supporting the drive shaft at its upper end. The drive shaft is supported against axial downward movement in the slide support structure by a thrust bearing 19 and lock nut 20.

The lower end of the drive shaft is constructed as an eccentric crank 21. The outer peripheral surface of the crank is circular and is received within a bore 22 of the rotor housing located centrally of the housing. The central axis of the rotor housing is shown at 22' in FIGS. 2 and 3. A retaining plug 23 is secured to the lower end of the crank 21 by screws such as shown at 24, to retain the shaft against lifting out of the rotor housing 5. A thrust bearing 25 provides a bearing support between the housing and the retaining plug. To facilitate relative rotation of the crank 21 in the bore 22 of the rotor housing a sleeve bearing 26 is fixed to the rotor housing.

At the upper end of the drive shaft, a pulley 27 is attached for receiving therearound a drive belt 28. The drive belt is run around a second pulley 29 connected to the drive shaft of a drive motor 30. Rotation of the drive shaft will, through the connection of the crank 21 with the rotor housing, provide a drive for rotating the rotor housing within the bore of the stator workpiece. With the eccentric connection of the drive shaft to the rotor housing and the gear construction 14, 15, the rotor housing will be restrained to move in precisely the same manner as the rotor part of the Wankel engine will move within the stator when these two parts are assembled into a motor.

In order to produce a proper honing of the interior bore surface of the stator workpiece, the honing members are adjustably mounted on the rotor housing. As shown in FIGS. 2 and 3, each of the members 6 includes a honing stone 31 for engaging the interior surface of the stator. These honing stones are constructed with a honing surface having the same radius of curvature as the sealing members of the rotor part of the Wankel engine. Holder means, comprised of two parts 32 and 33 pivotally connected to each other by a pin 34, are provided for holding the honing stones in a fully supported manner. As shown in FIG. 3, there are three honing members mounted about the periphery of the rotor housing. These members are spaced equally from each other about the center 22' of the rotor housing with the honing stones 31 located in precisely the same relative location as the sealing members of the rotor of a Wankel engine. The pivoting action of the two part holder for the stones permits them to properly engage the straight surface of the stator workpiece. The axis of pivoting extends perpendicular to the axis of the drive shaft and also perpendicular to the plane extending through the honing stone and the center about which all three honing members are positioned.

The holder means for each of the honing stones is slidably mounted on support means 35 through a key connection shown in FIG. 3. The engaging surfaces of the holder means and support means are inclined so that as the holder means is moved along the support means, the honing members will move radially toward and away from the interior bore surface of the stator workpiece. This radial movement is effected by raising and lowering the holder means and through the key connection of the part 33 to the support means 35.

For effecting radial adjustment of the position of the honing members, a control means is incorporated into the honing structure with a part thereof located remotely for actuation by the operator of the apparatus. This control means is operatively connected through the drive shaft to each of the honing members. In construction, it includes a control shaft 36 extending longitudinally through the drive shaft with one end 36' extending into the rotor housing and into a bore 37 formed in the crank 21. The longitudinal axis of the end 36' is coincident with the central axis 22' of the rotor housing. As shown in FIG. 2 the offset end 36' of the control shaft extends through the retaining plugs 23.

Disposed below the control shaft and in axial alignment therewith is a circular plate member 38. Along the periphery of this plate member, three connecting arms 39 are provided for connecting the plate to each of the parts 33 of the holder means. Only one of these connecting arms is shown in FIG. 2 and it is to be understood that identical structure is provided for each of

the other two honing members. Each of the arms 39 is L-shaped in configuration with a section 39' overlying the holder part 33 with which it is associated. A shoulder screw 40 is connected to the part 33 and extends loosely through an opening 41 in the arm section 39'. The plate 38 together with the arms 39, are mounted within the rotor housing for vertical sliding movement in a direction parallel to the axis of the drive shaft. Spring means 42 are provided for normally urging the parts 38, 39 upwardly; and due to the connection of the section 39' to the holder part 33 such upward movement will cause the honing stone holders to move upwardly along their inclined support surface and radially inwardly away from the interior surface of the stator workpiece.

To effect radial outward movement of the honing stones, the control shaft 36 is pushed axially downwardly to move the plate 38 and connecting arms 39 against the force of the springs 42. This axial movement of the control shaft is produced by actuation of a foot treadle mechanism connected through linkages to the upper end of the control shaft.

As shown in FIG. 2, a bearing retainer member 43 is fixed to the upper end of the control shaft for holding a thrust bearing 44 through which a plug member 45 extends. The upper surface of the plug member is engaged by a plunger 46 mounted on one end of a control lever 47. The control lever 47 is pivotally mounted intermediate its ends at 48 on a bracket 49 fixed to the slide structure 13. The other end of the control lever 47 has secured thereto a pusher rod 50. This pusher rod extends downwardly into a hollow rod the lower end of which is, as shown in FIG. 5, attached to one end of a foot treadle 52. The foot treadle 52 is, in turn, pivotally mounted at 53 so that depressing of its free end 54 will cause an upward movement of the hollow rod 51. This will continue until the upper end of the rod 51 contacts a collar member 55 secured to the rod 50. Further upward movement will cause the rod 50 to move upwardly and this will, in turn, cause the lever 47 to pivot about the axis 48 and press the plunger 46 downwardly against the plug 45 of the control shaft. The sliding connection of the pusher rod 50 within the hollow rod 51 permits raising of the entire honing mechanism during changing of the workpieces.

The extent to which the control shaft is pushed downwardly is controlled by the setting of a micrometer head 56 and a stop member 57. The lever will pivot counterclockwise about the axis 48 until it engages the stop member 57. The extent to which this pivoting movement has moved the control rod downwardly can be adjusted by adjusting the micrometer head 56 to, in turn, adjust the axial location of the plunger 46. An indicator 58 is associated with the micrometer head 56 for showing the operator the setting to which the head has been adjusted.

With the control shaft being pressed downwardly, its lower end 36' will engage and press the plate 38 downwardly against the force of the springs 42. The axis of the lower end 36' of the control shaft is coaxial with the center of the rotor housing and it engages the plate 38 at its center. Thus, the pressure applied to the plate will be distributed equally across the plate and cause a balanced movement of each of the honing members into pressure contact with the interior surface of the stator workpiece. Also, the engagement of the end 36' with the center of the plate will permit a single point of con-

tact between these two members as the drive shaft is rotated and its eccentric crank end rotates within the bore of the rotor housing.

In positioning the honing apparatus within the bore of the stator workpiece, it is essential that it be located in precisely the same way as the rotor of the Wankel engine. In order to facilitate this and to compensate for any misalignment relative to the workpiece, the workpiece is mounted on support structure which is free to float in two directions extending at right angles to each other. In particular, the support 4 comprises a first slide 59 supported on ball bushings by way of two rods 61 connected to the undersurface of the slide 59. This construction permits movement of the slide 59 to the right and left as viewed in FIG. 2. The bushings 60 are themselves mounted on a second slide 62, the undersurface of which is clamped to bushings 63. Each pair of these bushings is, in turn, slidably on a rod 64 secured to the primary support 65 for the entire apparatus. This second bearing support permits movement of the honing apparatus in a path perpendicular to the first sliding movement provided by the first mentioned rod and bushing connection. The maximum degree of movement necessary to compensate for misalignment and to assure accurate positioning of the honing apparatus within the bore of the stator workpiece need be no more than 0.015 inch.

FIGS. 1-5 show the preferred embodiment of the present invention wherein mechanical control means are used for adjusting the positioning of the honing members. As an alternative embodiment of the invention, pneumatic or hydraulic means may be used for this purpose. Such a construction is shown in FIG. 6 where like reference numerals followed by the suffic prime (') are used for designating like parts. Here, each of the honing members is pivotally mounted on the end of a piston rod 66 of a hydraulic power cylinder assembly. One assembly is provided for each of the honing members and positioned in spaced relation about the rotor housing 5 in the same manner as the support means for the honing members used in the embodiment of the invention shown in FIGS. 1-6. A source of fluid pressure 68 disposed externally of the honing mechanism is connected to each of the power cylinder assemblies 67 by way of a conduit 69 extending through the drive shaft 16' and into the crank end 21'. One or more branch conduits 70 connect conduit 69 to a channel 71 formed in the periphery of the crank 21'. This channel is located in communication with an inlet to each of the power cylinder assemblies 67. Seals 72 are provided on the periphery of the crank 21' to prevent escape of fluid pressure from the bore of the rotor housing in which the crank is rotatably positioned.

Applying pressure to the cylinder will cause the honing members to move radially outwardly into pressure contact with the interior bore surface 7 of the stator workpiece 3. When it is desired to retract the honing members to permit raising of the rotor housing out of the workpiece and insertion into a new workpiece, the pressure to the cylinder assemblies is removed. Springs 73 will then take over and move the honing members to retracted positions. The spring 73 associated with each of the honing members is mounted in the rotor housing with one end engaging against the housing and the other end engaging against a stud 74 connected to the honing members. The force of the spring normally urges the honing members into retracted position.

I claim:

1. A honing apparatus for honing the interior bore surface of a stator member in which a rotor member is to rotate in a predetermined manner with three equally spaced points on the rotor making continuous engagement with said surface, said apparatus comprising:
  - a. support means for supporting said stator member in a predetermined plane;
  - b. a honing rotor housing positionable within the bore of said stator member;
  - c. means for supporting said housing in the bore of said stator member for rotation in said plane;
  - d. three honing members mounted on said housing at equally spaced points about a central common axis in the same manner as the three points on said rotor member for engagement with the interior bore surface of said stator member, each of the honing members comprising:
    1. a honing stone for engaging the interior surface of said stator, and
    2. holder means for the honing stone;
  - e. support means for mounting said honing stones for radial movement toward and away from the interior bore surface of the stator member, said support means including a supporting surface inclined relative to the radial movement of the honing stones for engaging the holder means for movement therewith to effect said radial movement of the honing stones;
  - f. drive means for rotating said rotor housing in the same predetermined manner as said rotor member is to rotate to move said honing members along the interior bore surface of the stator while in continuous engagement therewith, including:
    1. a drive shaft connected to said rotor housing, extending perpendicular to said plane, and into said rotor housing in rotatable relation therewith at a point offset from the center about which the three honing members are mounted, and
    2. power means for rotating said drive shaft; and
    - g. control means for adjusting the radial location of said honing members, said control means being partially disposed externally of said drive means and operatively connected through said drive shaft to the support means mounting the honing members, including:
      1. a control shaft mounted for axial movement within said drive shaft with one end extending into said rotor housing and aligned with the center about which the three honing members are mounted,
      2. a first part connected to the other end of said control shaft for moving the control shaft axially within said drive shaft,
      3. a second part defined by a single plate mounted in said rotor housing in axial alignment with the one end of said control shaft for movement in response to axial movement of said control shaft, and
      4. a third part mounted in said rotor housing for movement in a direction parallel to the axis of said drive shaft and comprising three arms, each of which is connected at one end to said plate and at its other end to one of the support means for the honing members.
  2. A honing apparatus according to claim 1 further comprising:

- a. a fixed gear having external teeth mounted concentrically to said drive shaft;
- b. an internal gear fixed to said rotor housing and disposed in meshing, surrounding relation with said fixed gear, and
- c. crank means fixed to the one end of said drive shaft and disposed within said rotor housing, said crank means having a circular periphery rotatably received within a complementary shaped circular bore in said rotor housing, said bore having a central axis parallel to and offset from the longitudinal axis of said drive shaft.

3. A honing apparatus for honing the interior epitrochoidal bore surface of a stator member according to claim 2 wherein:

- a. the gear ratio between the internal and fixed gears is 3:2;
- b. the center of the circular bore of the rotor housing coincides with the center about which the three honing members are mounted; and
- c. the control shaft has an offset end aligned with the center of said bore and extending through the crank means and into contact with the center of

said plate.

4. A honing apparatus according to claim 2 further comprising:

- a. means for mounting the support means for the stator workpiece for movement in said plane in two directions, perpendicular to each other.

5. A honing apparatus according to claim 2 further including:

- a. spring means for urging said honing members radially inwardly away from the interior bore surface of said stator workpiece.

6. A honing apparatus according to claim 5 wherein:

a. the first part of said control means comprises:

- 1. a pivotally mounted lever having one end overlying the other end of said control shaft exteriorly of said drive shaft,

- 2. a push rod connected to the other end of said lever, and

- 3. foot treadle means connected to the other end of said push rod for controlling movement thereof.
